UNITED STATES PATENT OFFICE.

D. W. KENNEDY, OF STAUNTON, VIRGINIA.

DRYING CLOTH.

Specification of Letters Patent No. 11,163, dated June 27, 1854.

To all whom it may concern:

Be it known that I, D. W. KENNEDY, of Staunton, in the county of Augusta and State of Virginia, have invented certain new and useful Improvements in Apparatus for Tentering and Drying Cloth; and I do hereby declare that the following is a full, clear, and exact description of the same, reference being had to the accompanying drawings, forming part of this specification, in which—

Figure 1, is a longitudinal vertical section of an apparatus constructed according to my invention. Fig. 2, is a transverse vertical section of the same.

Similar letters of reference indicate corresponding parts in both figures.

To enable those skilled in the art to make and use my invention, I will proceed to describe its construction and operation.

A, A, are two standards, which support in suitable bearings, the shaft, B, which carries the wheels or open disks, C, C'. The shaft, B, is hollow, and is connected at one end by a stuffing box, D, with a steam or hot air pipe, E; and at the other end, by a similar stuffing box, with a discharge pipe, F. It is enlarged at that part between the wheels in the form of a drum, G. The wheels, C, C', consist each of a hub, a; arms, b, b'; a spiral strip, c, c, attached to the arms, and making several volutions, and a rim, d. They may be built of wood, or may be of cast iron, cast all in one piece. One is made of a form exactly the reverse of the other, in order that when the spiral strips, c, c, face each other, they may correspond exactly. The tenter hooks, e, e, are secured in the spiral strips at suitable distances apart, so that they run spirally round the faces of the wheels, or disks. The wheel, or disk, C, is secured to the shaft, B, in a fixed position, but the other, C', is movable, being fitted by a female thread in its eye center, on a male screw on the shaft, so that by turning it on the shaft the distance between the two series of tenter hooks may be varied for cloths of different widths. A key way should be cut, partly in the shaft, and partly in the hub of C', to receive a key for the purpose of securing the wheel to the shaft with its spiral row of hooks opposite those of the other wheel. In rear of the wheels, C, C', parallel with their shaft, and nearly on a level with the top of them, is a roller, H, which turns freely in bearings in arms, I, I,

which stand out from the backs of the standards. This roller serves as a guide to the cloth during the operation of stretching it between the wheels. The shaft, B, is furnished with fast and loose pulleys, J, J', and receives rotary motion from any suitable prime mover. It is also furnished with a ratchet wheel, K, into which engages a pawl, L, (see Fig. 2), attached to one of the standards, for the purpose of preventing the turning of the shaft in any but the direction indicated by the arrow in Fig. 2.

The cloth is stretched and dried in the following manner. The wheel, C', is previously adjusted to its proper position on the shaft according to the width of the cloth, and made secure. The end of the piece is then brought over the roller, H, and both sides attached to the tenter hooks at the inmost extremity, f, (see Fig. 2), of the spiral line. The shaft is then gradually turned to allow the cloth to be hooked on the tenter hooks until the whole piece is hooked on, when its position is as represented in red outline in Figs. 1, and 2. The shaft is then set in motion at a speed of about four hundred (400) revolutions in a minute, and the rapid revolution of the cloth in the direction of the arrow causes a partial vacuum to be produced behind the opening or extremity, g, of the space between the volutions of the cloth, causing currents of air to rush through the openings in the wheels or disks to fill the said vacuum. A rapid circulation of air is thus caused between the several volutions of the cloth, and this, assisted by the heated cylinder, G, produces a speedy evaporation and escape of all the moisture from the cloth.

Thus, it will be observed that, the drying is effected partly by the current of air which the cloth creates when in motion, and partly by the radiation of heat from the hot air or steam drum, which, by its central position, causes the cloth to be uniformly dried throughout its length on the scroll, the hot air drum giving out most heat on that portion of the cloth nearest the center, where the motion of the reel is slowest and the drying current, created by the cloth in motion, least, and imparting, in a regular ratio, less heat upon the cloth as the volutions increase and the drying current, by reason of the increasing rapidity in motion of the cloth toward the periphery of the reel, becomes stronger. By this combination and arrange-

ment of the hot air or steam drum and spiral position of the cloth on the reel, with sufficient air space between the volutions, a long length of cloth may be dried more rapidly, 5 economically and uniformly in a small compass or space than by any known arrangement in which the cloth is spread open and made to cover a greater and inconvenient length of space.

10 A piece of cloth, forty (40) yards in length may be dried by this apparatus in about forty minutes.

The apparatus occupies but little room; its size may be varied to suit circumstances.

15 The space between the several volutions of the cloth will not usually require to be more than two inches. This measurement will, in some degree, serve as a guide for the diameter of the wheels, which will be dependent

20 on the length of the piece of cloth.

I do not claim as new, the revolving reel

or heads having the cloth to be dried wound spirally between the heads, with a continuous air space between the volutions; nor do I claim, in itself, for drying cloth, the employment of a revolving hot air or steam drum; but—

I do claim as new and useful, and desire to secure by Letters Patent—

The reel constructed as described in combination with the hot air, or steam, drum arranged upon its shaft; whereby the cloth near the shaft may be dried equally with that upon the outer diameter of the reel and thus equalize the shrinkage of the cloth 35 throughout its whole length, in the manner set forth.

D. W. KENNEDY.
